BASILE SOLDATENCOW, OF PARIS, FRANCE.

ELECTROMAGNETICALLY-CONTROLLED KEYBOARD FOR PERFORATING APPARATUS.

1,100,501.

Specification of Letters Patent. Patented June 16, 1914.

Application filed January 8, 1913. Serial No. 740,815.

To all whom it may concern:

Be it known that I, BASILE SOLDATENCOW, of 37 Rue La Pérouse, Paris, France, have invented certain new and useful Improvements in and Relating to an Electromagnetically-Controlled Keyboard for Perforating Apparatus, of which the following is a specification.

This invention has for its object to provide an electro-magnetically controlled keyboard for perforating machines intended for the perforation of the bands of paper utilized for telegraphic apparatus for example and it is mainly intended for increasing the rapidity of perforation while at the same time rendering the machine strong and insuring certainty in operation.

In the accompanying drawing which illustrates an embodiment of the invention by way of example: Figure 1 is a vertical cross section of the device on the line 1—1 in Fig. 2. Fig. 2 is a plan thereof partly broken away. Fig. 3 is a detail. Fig. 4 is a diagram of the connections. Fig. 5 shows diagrammatically a modification of parts of Fig. 2.

Upon the bottom *a* of a box *b* intended to support the perforating mechanism proper which may be of any appropriate construction and is not shown, an insulating plate *c* of ebonite for example is mounted and supports metal bars *d* running longitudinally of the apparatus and in which pump contacts *e* are housed which are in constant electrical communication with these bars.

The metal bars *d* (thirteen of which may be provided for example) are represented more clearly in Figs. 2 and 4; they are connected with metal contacts mounted on the insulating plate *f* supported by the lid of the box *b*. These contacts which are arranged upon one and the same circumference concentric with the axis of the plate *f* are arranged in two series *g*, *g'* . . . *g''* (eight in number for example) arranged opposite a metal segment *i* connected by the conductor *x* with a solenoid actuating the perforating punches, the combination of which forms the dash (—). Fig. 4 shows that the bars 1, 2, 4, 6, 8, 10, 12 and 13 are thus intended to control the dashes.

The intermediate bars, that is to say 3, 5, 7, 9 and 11 are connected by means of conductors with contact pieces *h*, *h'* . . . *h''*

(five of them being provided for example) 55 arranged in the same manner opposite a metal segment *j* connected by a conductor *y* with a solenoid controlling the operation of the punches, the combination of which forms the dot (·).

As shown in Fig. 2 the number of pumps *e* arranged in each transverse row varies in such a manner as to realize the various combinations of dashes and dots of the Morse alphabet and above each of the transverse 65 rows there is arranged a lever *k* pivoted at *m* in the bottom of the box and provided with an operating key *n* upon which the corresponding alphabetical character is marked.

Each key comprises a counter spring *o* and the front extremity of the levers *k* following a chamfer *p* is located opposite a boss *q* carried by one of the extremities of a lever *r* pivoted at *s* on the box or frame 75 while the other extremity is pivoted to a rod *u* connected on the other hand with the armature *v* of the fixed core *w* of a solenoid 13 located inside the box *b*. At their front extremity the levers *k* bear upon a cross bar 80 *t* supported by levers *s* pivoted at *s* to the frame and this bar is able to engage with a contact *z* at which the leading-in wire 37 for the current terminates.

The solenoid 13 housed inside the box *b* 85 comprises in addition to its fixed core *w* a movable core 14 supported by a rocking arm 15 pivoted to a fixed bracket 16 one of its extremities actuating the shaft 17 of a brush holder arm 18 by means of a suitable ratchet. 90 This arm which is of insulating material supports at each of its two extremities a double bridge-shaped brush 19 intended for placing the contacts of the outer line *g* and *h* in communication with the corresponding 95 segments *i*, *j*.

The arm 15 is of conducting material and its pivot 38 being connected with the mass like the levers *k* provided with keys, when one of these levers *k* is depressed in order 100 to bring the bar *t* into engagement with the contact *z* a current will circulate throughout the entire casing of the apparatus and will terminate at the pivot 38 of the lever 15/20. In the normal position of the lever 15, that 105 is to say when the solenoid 13 is not energized this part 20 can rest upon a terminal 21 connected by a conductor 26 with the

leading-in wire of the solenoid 13 while for the position of attraction of the solenoid 13 the part 20 rests upon a stop 22.

The leading-in wire 26 of the solenoid is also connected by a conductor 23 with a contact piece 24 carried by the insulating plate *f* and which one of the brushes 19 can place in communication with another contact piece 25 connected with the mass 10 and consequently acting as leading-in contact for the current. The leading-out wire of the solenoid 13 is connected by a conductor 39 with a return terminal not here shown.

15 The double ring of contacts also comprises a contact piece 27 connected by a conductor 28 with the spacing solenoid and which can be placed in communication by a brush 19 with a contact piece 29 connected with a fixed contact 30 insulated from the mass and arranged opposite a movable contact 31 connected with the mass and controlled by the spacing bar 32 which is acted upon by a contour spring.

25 Each of the bent levers 34 supporting the bar *t* comprises an extremity 40 terminating in front of the rod 41 of a press button 42 carried by a leaf spring 43 (Fig. 4) provided at its extremity with a contact 44 engaging with a fixed contact 45 insulated from the mass and connected by means of a conductor not here shown with the contact piece 25 of the plate *f* in such a manner that this contact piece 25 is only connected with 30 the mass when the button 42 is not pressed and occupies the position represented in Fig. 4.

The operation is as follows: When a key corresponding to the letter P for example 40 is pressed this letter being reproduced in the Morse alphabet by the signs - - - in order to obtain this combination the key depressed depresses the pumps of the bars 2, 3, 5 and 6. Now by the depression of the key P, as its 45 lever *k* occupies the position represented in broken lines in Fig. 3 where it is held depressed by the boss *q*, the contacts *t*-*z* are placed in communication and the current supplied through the conductor 37 proceeds 50 to the mass of the apparatus, then through the bracket 16 to the part 20 of the lever 15 in contact with the terminal 21 in such a manner that the current coming from the mass energizes the solenoid 13 and attracts 55 its movable core 14. This attraction produces a partial rotation of the shaft 17 and the brush holder 18 brings one of the brushes 19 upon the contact *h* while at the same time the other brush 19 reaches the contact 60 *g*. This contact *g* corresponding to the bar 1 being deprived of current the solenoid for the dashes is not energized. The other brush 19 placing in communication the contact piece *h* connected with the bar 3 (the pump 65 *e* of which is depressed) with the corre-

sponding ring *j* the current then passes through the conductor *t*, the bar *z*, the lever *k*, the pump *e*, the bar 3, the contact *h* and the segment *j* and through the conductor *y* energizes the solenoid for the dots which in 70 the known manner controls the play of the perforations corresponding to the dots in simultaneously causing the band of paper which is being perforated to advance to the extent of one division. During this attraction of the core 14 the lever 20 has reached the stop 22 which is currentless and the excitation of this solenoid 13 ceases as 75 well as the attraction of the movable core and the latter returned by a spring (not shown), resumes the position shown in Fig. 2 with its conducting lever upon the terminal 21 a fresh attraction of the solenoid 13 takes place which again attracts the core 14 in producing a 80 further partial rotation of the shaft 17 and of the brush holder 18. The brush 18 of the contacts *h* reaches the currentless contact piece *h'* the bar 3 comprising no pump beneath the lever of the depressed key *n* while the brush 19 of the contacts *g* reaches the contact piece *g'* connected with the bar 2 provided with a pump. The current coming from the contact *t*-*z* then energizes the solenoid for the dashes 85 which controls the corresponding set of perforators. This attraction of the core 14 has again interrupted the current of the solenoid 13, the lever 20 of which returns to the contact 21 so as to produce a fresh attraction 90 of the core 14 and the consequent displacement of the brush holder 18 which brings the brushes 19 onto the contacts *g'* and *h'* and owing to the presence of a pump upon the bar 4 causes a current to pass 95 through the contact *g'* producing the excitation of the solenoid for the dashes. The operation is reproduced until the last excitation of the perforating solenoids has been produced. From this moment no current 100 passes to these solenoids but the mass current which still reaches the solenoid 13 continues to control the rotation of the brush holder 18. When the brush 19 of the contacts *g* reaches the contact 27, 29 it sends 105 through the conductor 28 into the spacing solenoid a current which causes the band of paper which is being perforated to advance by one division in the known manner and then upon the following impulsion of the 110 solenoid 13 this brush 19 of the contacts *g* passes to the contacts 24 and 25. The contacts 25 being connected with the mass the solenoid is short-circuited through 25, 24, 115 23, 39 and the excitation of the solenoid 13 120 then becomes sufficient for energizing the fixed core *w* and attracting the armature *r* which in acting upon the lever *r* releases the lever *k*. The latter is then pressed back by its counter spring *o* and the contact *t* leaves 125 130

the contact z and returns to the position shown in Fig. 1. This operation takes place at each depression of a key.

In order to prevent, during the rotation of the brushes, sparks on opening and closing on the several contacts, which sparks might, owing to the relatively great intensity of current, result in a rapid deterioration of the contacts, contact blades are arranged, as shown in Fig. 5, which blades are separated from each other by insulating blades 46, in order to form external contact rows g , g' , etc., and h , h' , etc., and internal contact rows i , 27, 24 and j . The size of these contacts is larger than required to determinate the impulses in the perforating solenoids, and the impulse of current is determinated in each case by a switch having, as shown by Fig. 5, a lever 47 pivoted at 48, one end of which is held into contact by means of a spring 51 with the teeth of a ratchet wheel 49 fixed on the shaft 17. The other end of this lever has a contact piece 50 placed in front of a contact 51 supported by an adjustable screw 52. The two contact pieces 50 and 51 together form a switch in the circuit supplying the contacts of the two concentric contact rows. As a consequence of such arrangement it occurs that when the solenoid 13 is energized and when its core is attracted, said core in its downward movement causes the shaft 17 to rotate together with the ratchet wheel 49. The latter oscillates the lever 47 which separates the contacts 50 and 51. The various parts are arranged in such manner that, when the brushes 18, 19 begin to move on their contacts the circuit is not yet broken; but when the brushes approach the insulating blades 46 the circuit is broken so that the brushes can move from one contact to the next without any production of sparks, because at the moment of such passage the contacts are deprived of current. Thus the sparks appear only between the contacts 50 and 51 easily removable, and further the position of the contact 51 is adjustable by means of the screw 52 so that the interruption be produced at the desired moment.

When it is desired to feed the band of paper being perforated without producing fresh perforations the button 42 is depressed without depressing a key. This button separates the contacts 44 and 45 and by pressing upon the lever 40 brings the bar t into contact with z in such a manner that the solenoid 13 is energized and actuates its movable core 14 for producing the rotation of the brush holder 18. This rotation takes place intermittently as in the preceding case but as the contacts g and h are currentless there is no excitation of the solenoids for the dashes and dots.

When a brush 19 comes onto the contacts 27, 29 the current proceeds to the spacing

solenoid and causes the band of paper to advance. When the brush 19 comes upon the contacts 24, 25 as the contacts 44, 45 are separated the solenoid 13 is not short-circuited and continues to be energized only by the intermediary of its arm 20 in such a manner that so long as the button 42 is depressed the shaft 17 rotates and twice per revolution (when the brushes 19 pass over the contacts 27, 29) energizes the spacing solenoid which produces the paper feed.

The advantages are as follows: It should first of all be noted that the solenoid 13 is only energized by the current supplied through the wire 26 to a sufficient extent to produce the attraction of its movable core 14 while this excitation is insufficient for energizing the fixed core w for controlling the attraction of the armature v . Only the current coming through the terminal 25 and the conductor 23 circulates in the solenoid for a sufficient time to attract this armature v by energizing the core w .

The arrangement described in producing for each depression of a key the rotation of the brush holder 18 for a half revolution until one of the brushes 19 unites the contacts 24 and 25 insures a uniform duration of the operation of the apparatus whatever the sign to be transmitted may be, that is to say whatever number of perforations have to be made. Furthermore as the transmission of the current takes place by means of a brush which passes over contacts embedded in an insulating plate no shocks are produced thereby increasing the certainty of operation and at the same time the life of the apparatus while also facilitating its maintenance. On the other hand the arrangement of the single solenoid 13 for effecting all the functions of control of the keyboard effects an economy in installation and also an economy of current as compared with known apparatus which comprises a continuously running motor. Instead of providing the solenoid 13 with a movable core and a fixed core the excitation of which produces the liberation of the parts and their return to the normal position this return might be controlled by an independent electromagnet or any other part of desired construction.

It is also possible instead of the arrangement of conducting bars connected with the various contacts that has been described to provide bars of insulating material in which conducting pumps are screwed and appropriately arranged for the production of the desired signs and connected one with the other in any desired manner and also with the contacts controlling the perforating solenoids. In this case only a single ring of contacts might be provided together with a single brush by connecting the shaft of the brush holder made of conducting material with the mass. The ar-

angement described presents the advantage, however, of being simpler in construction and more economical and also of being more certain in its operation.

3. In order to reduce the dimensions of the apparatus two or a larger number of different signs might be controlled by one and the same key. With this object the conducting bars might for example be fitted to a moving 10 carriage and provided with the pump housings in suitable proximity to the levers of the corresponding keys in such a manner that when the carriage and the bars are displaced by means of an appropriate control 15 different combinations of pumps from those obtained when the carriage with the bars is at rest are brought beneath the levers. By suitably regulating the direction and the amplitude of the displacement of this carriage two or more combinations of contacts can be controlled by each key and it is also possible to render the assemblage of keys and key bars movable or the mobility of the bars and of the keys can be combined. In 20 order to reduce the bulk of the keyboard the key levers might also be arranged in two sections insulated one from the other, one of these sections controlling by the usual operation the movement of the perforating 25 solenoids, while the other section would be integral with a special contact which would then be operated at the same time as the perforating keys. It is also possible for controlling the second series of signs to provide two sets of pumps end to end at different levels, the depression of the corresponding lever being suitably limited by a disappearing stop provided with an appropriate 30 operating member.

40. The invention is applicable to the perforation of bands of paper such for example as those employed in telegraphy and generally speaking, in all cases in which it is desired to produce current impulses either at regular 45 intervals or otherwise.

What I claim is:

1. In an electro-magnetically controlled key-board for perforating machines, a plurality of solenoids for actuating the perforating mechanism, conducting segments in electrical connection with said solenoids, contacts connected with said conducting segments, a differential solenoid having a movable core, a shaft controlled by said movable core, a rotary arm carried by the shaft, and brushes carried by said rotary arm and arranged to be brought into engagement with said contacts.

2. In an electro-magnetically controlled key-board for perforating machines, a plurality of solenoids for actuating the perforating mechanism, conducting segments in electrical connection with said solenoids, contacts connected with said conducting segments, a differential solenoid having a mov-

able core, a shaft controlled by said movable core, a rotary arm carried by the shaft, brushes carried by said rotary arm and arranged to be brought into engagement with said contacts, an insulating frame, concentric bars supported in said insulating frame, and operating levers provided with keys arranged above said concentric bars. 70

3. In an electro-magnetically controlled keyboard for perforating machines, a plurality of solenoids for actuating the perforating mechanism, conducting segments in electrical connection with said solenoids, contacts connected with said conducting segments, a differential solenoid having a movable core, a shaft controlled by said movable core, a rotary arm carried by the shaft, brushes carried by said rotary arm and arranged to be brought into engagement with said contacts, an insulating frame, concentric bars supported in said insulating frame, operating levers provided with keys arranged above said concentric bars, and a series of annularly arranged contacts connected with said concentric bars, said annularly arranged contacts being disposed opposite said first named contacts. 80

4. In an electro-magnetically controlled keyboard for perforating machines, a solenoid having a movable core, a pivoted conducting arm, said core being pivotally connected to said movable arm, a pair of opposed adjustable contact members, one of said adjustable opposed contact members being connected with the winding of said solenoid, the end of said pivoted arm on the opposite side of its pivotal connection with the core of the solenoid being arranged to bear on one of said opposed contacts in one position of the core and on the other of said contact members in another position. 95

5. In an electro-magnetically controlled keyboard for perforating machines, a solenoid having a movable core, a pivoted conducting arm, said core being pivotally connected to said movable arm, a pair of opposed adjustable contact members, one of said adjustable opposed contact members being connected with the winding of said solenoid, the end of said pivoted arm on the opposite side of its pivotal connection with the core of the solenoid being arranged to bear on one of said opposed contacts in one position of the core and on the other of said contact members in another position, a brush holder, a shaft therefor, a ratchet carried by said shaft, and means carried by said pivoted arm for actuating said ratchet. 110

6. In an electro-magnetically controlled keyboard for perforating machines, a solenoid having a movable core, a pivoted conducting arm, said core being pivotally connected to said movable arm, a pair of opposed adjustable contact members, one of

- said adjustable opposed contact members being connected with the winding of said solenoid, the end of said pivoted arm on the opposite side of its pivotal connection with 5 the core of the solenoid being arranged to bear on one of said opposed contacts in one position of the core and on the other of said contact members in another position, a brush holder, a shaft therefor, a ratchet 10 carried by said shaft, means carried by said pivoted arm for actuating said ratchet, brushes carried by said brush holder, and concentric rows of contacts arranged to be engaged by said brushes in the movement 15 of said brush holder, one of the contacts in said concentric rows being connected with the winding of said solenoid.
7. In an electro-magnetically controlled keyboard for perforating machines, a solenoid having a movable core, a pivoted conducting arm, said core being pivotally connected to said movable arm, a pair of opposed adjustable contact members, one of said adjustable opposed contact members being 20 connected with the winding of said solenoid, the end of said pivoted arm on the opposite side of its pivotal connection with the core of the solenoid being arranged to bear on one of said opposed contacts in one 25 position of the core and on the other of said contact members in another position, a brush holder, a shaft therefor, a ratchet carried by said shaft, means carried by said pivoted arm for actuating said ratchet, 30 brushes carried by said brush holder, concentric rows of contacts arranged to be engaged by said brushes in the movement of said brush holder, one of the contacts in said concentric rows being connected with 35 the winding of said solenoid, the companion contact in another of said concentric rows of contacts being connected with a lead wire of one sign, one of said opposed adjustable contact members being connected 40 with the lead wire of the same sign, and connections between the solenoid and the lead wire of the opposite sign.
8. In an electro-magnetically controlled keyboard for perforating machines, a plurality of spaced contacting segments, means 45 movable over said segments and adapted to contact therewith for connecting the segments as the same move thereover, an electro-magnetic member for actuating said means, and conductor connecting means for connecting said electro-magnet member and said segments with a source of current.
9. In an electro-magnetically controlled 50 keyboard for perforating machines, a plurality of spaced segments, a movable connecting member adapted to be moved over said segments and connecting the segments as it is moved thereover, a supporting member for said means, a solenoid, and means operated by said solenoid for moving the

member supporting said segment connecting means, whereby when said solenoid is energized said segment connecting means will be moved.

10. In an electro-magnetically controlled 70 keyboard for perforating machines, a plurality of spaced segments, a source of current, a key mechanism for connecting said source of current to certain of said segments, a movable connecting member for said segments, and means including a solenoid for moving said segment connecting means over all of said segments whenever any of said keys are operated, whereby the energized segments are connected.

11. In an electro-magnetically controlled 80 keyboard for perforating machines, a plurality of spaced segments, a plurality of key mechanisms for connecting a source of current to some of said segments, means for 85 connecting the remaining segments to a perforating apparatus, a connecting member adapted to move over said segments, and connect the energized segments with the segments connected with said perforating apparatus, and means for moving said connecting member including a solenoid.

12. In an electro-magnetically controlled 90 keyboard for perforating machines, a line of spaced segments, a second line of spaced segments arranged substantially parallel with said first mentioned line of segments, a plurality of key operated mechanisms for connecting current to the segments in said first line of segments, a connecting member 95 adapted to span both of said lines of segments, and means set in motion by the operation of said keys for moving said connecting member over said lines of segments whereby the respective segments of one line are 100 connected at certain intervals with the segments of the other line of segments.

13. In an electro-magnetically controlled 110 keyboard for perforating machines, a plurality of spaced segments arranged substantially in a circle, a second line of segments arranged substantially in a circle and spaced from said first mentioned line of segments, key operated mechanism for connecting a source of current supply to certain of the 115 segments in said first line of segments, a rotating arm adapted to move over all of said segments, a connecting member arranged at each end of said arm for connecting the first row of segments with the second row of segments, a solenoid, and means operated by the solenoid for moving said arm step by step 120 over said rows of segments.

14. In an electro-magnetically controlled 125 keyboard for perforating machines, a plurality of lines of spaced segments, key operated means for connecting a source of current to certain of said segments, a rotating arm adapted to pass over said segments, a connecting member arranged on each end 130

of said arm adapted to connect the segments in each line of segments as the same passes thereover, a shaft for supporting said arm, a ratchet wheel connected with said shaft, a 5 pivotally mounted member for actuating said ratchet wheel, and a solenoid for actuating said pivotally mounted member.

In testimony whereof I have hereunto placed my hand at Paris, France, this 17th day of December 1912.

BASILE SOLDATENCOW.

In the presence of two witnesses:

HANSON C. COXE,
LOUIS COQUILLOT.
